Attorney.

UNITED STATES PATENT OFFICE.

MILLARD F. ATKINSON, OF PALMYRA, NEW JERSEY.

CARD-FEEDING DEVICE FOR PRINTING PRESSES.

Application filed September 29, 1922. Serial No. 591,271.

To all whom it may concern:

Be it known that I, MILLARD F. ATKINSON, a citizen of the United States, residing at Palmyra, in the county of Burlington and State of New Jersey, have invented certain new and useful Improvements in Card-Feeding Devices for Printing Presses, of which the following is a specification.

This invention relates to improvements in 10 card feeding devices for printing presses and other machines.

The object of the invention is to provide a novel, simple and efficient mechanism which will feed cards successively from a 15 first position within a card containing magazine to a second position forwardly of the magazine, and from the second position to a third or impression receiving position forwardly of the second position.

With the foregoing and related objects in view, the invention consists in the novel construction, combination and arrangement of parts hereinafter described and claimed.

In the accompanying drawings, illustrating the invention,

Figure 1 is a sectional plan view of a printing press provided with a card feeding device embodying my invention.

Figure 2 is a central longitudinal section 30 thereof, on line 2—2 of Fig. 1.

Figure 3 is a longitudinal section of the machine, on line 3—3 of Fig. 1, showing the card feeders in the rearward position.

Figure 4 is a view similar to Fig. 3, showing the card feeders in the forward position.

Figure 5 is a transverse section of the machine, on line 5—5 of Fig. 1.

Figure 6 is a transverse section on line 6—6 of Fig. 2.

Referring to the drawings, 6 designates the base frame of the machine and 7 a table supported thereon. Upon the table 7 near the rearward end thereof is a magazine 8 adapted to contain a stack or quantity of 45 cards A to be printed; and upon the table 7 near the forward end thereof is a tympan 9 to which the cards A are moved successively from within the magazine 8 by mechanism hereinafter described. Above the 50 tympan 9 is a type carrying member 10, which is pivoted, at 11, on brackets 12 projecting fixedly from the forward end of the table 7. The member 10 is provided with a removable chase 13 which is clamped thereto and which holds the form or type 14 in the usual manner. The member 10

is adapted to be raised and lowered by suitable mechanism, not shown, to effect the printing of the cards A as they successively occupy positions upon the tympan 9. 60

The magazine 8 comprises a front wall 15, side walls 16, a rear wall 17 and a bottom formed by the upper surface of the table 7. The front wall 15 is secured to brackets 18, which are secured to the table 7. 65 The rear wall 17 is formed integral with and extends upwardly from the forward end of a plate 19 which rests upon the table 7 and has a longitudinal slot 20 formed therein.

The plate 19 and therewith the rear wall 17 of the magazine are adapted to be adjusted toward and from the front wall 15 and to be held in different positions of adjustment by set screw 21 extending through the 75 slot 20 and screwed into the table 7. The wall 17 is maintained in parallel relation to the wall 15 during the adjustment of the wall 17 by the screw 21 and a projection 22 extending downwardly from one side of the 80 plate 19 and into a guide slot 23 in the table 7.

The side walls 16 of the magazine are secured to and extend upwardly from the rearward extensions 24 of two side plates 25 which rest upon the table 7, the extensions 24 extending between the front wall 15 of the magazine 8 and the inner or opposing vertical surfaces of the plates 25, forming, in effect, continuations of the magazine side 90 walls 16.

The inner or opposing surfaces of the plates 25 extend from the magazine 8 to the tympan 9 and form guides for the ends of the cards A as they are projected successively 95 from the magazine to the tympan. The plates 25 are provided with thin ledges 26 which extend inwardly from the bottom of the inner surfaces of the plates and rest upon the table 7 and are adapted to receive 100 the edge portions of the ends of the cards A which are moved over the ledges 26 while being guided by the plates 25. Above the ledges 26 are bars 27 which extend between the forward ends of the plates 25 and the front wall 15 of the magazine 8 and which are carried by flat springs 28 secured on the plates 25. When the cards A are guided by the plates 25, the end edge portions of the 105 cards pass between the ledges 26 and the bars 27, and the bars 27 serve to hold the cards down upon the ledges. The rearward

ends of the bars 27 are beveled to insure the passage of the cards beneath them when the cards leave the magazine 8.

As a means to simultaneously adjust the guide plates 25 and therewith the side walls 16 of the magazine toward and from each other to accommodate cards of different lengths, I provide the following: Extending transversely across the machine above the plates 25 is a shaft 29 which is mounted to turn in bearings 30 rising from the sides of the table 7. One end of the shaft 29 is provided with a hand wheel 31 by means of which the shaft may be turned. The respective end portions of the shaft 29 are provided with oppositely-pitched screw-threads which are screwed into and through brackets 32 on the guide plates 25 whereby the plates 25 and wall 16 may be adjusted either toward or from each other as desired by turning the shaft 29.

Formed on the bottom of the table 7 are downwardly extending ribs 33 which extend longitudinally of the machine and form guideways 34 for the reception of the lateral guiding ribs 35 of a block or cross-head 36 which is mounted to slide longitudinally within the guideways 34. The block 36 is provided with a pair of rearward card feeders 37 and a pair of forward card feeders 38 which extend upwardly from the block 36 and into and through parallel openings 49 in the table 7. The forward edge portions of the card feeders 37 and 38 extend above the plane of the upper surface of the table 7 a distance equal or substantially equal to the thickness of one of the cards A, and the top surfaces of the feeders 37 and 38 are beveled rearwardly and downwardly so that their rearward edges are below the plane of the upper surface of the table 7, so that, when the block 36 is moved forwardly, the forward edges of the feeders 37 and 38 will engage the rearward edges of cards upon the table 7 and which they encounter in their paths and feed them forwardly, and so that, when the block 36 is moved rearwardly, the feeders 37 and 38 will pass beneath and slightly raise the cards which they encounter in their paths and pass beneath them.

The block or cross-head 36 is connected by the link 39 to an arm 40 extending from a rock shaft 41 which is mounted to be rocked in suitable bearings in the base frame 6. The shaft 41 is provided with an arm 42 having a bar 43 connected thereto by means of which the shaft 41 may be rocked to reciprocate the block 36 and thereby move it and therewith the card feeders 37 and 38 forwardly from the position shown in Fig. 3 to the position shown in Fig. 4 and back again. The bar 43 may be operated by the mechanism of the printing press or otherwise.

During the reciprocations of the block 36

the card feeders 37 are adapted to move the cards A successively from within the magazine to the position A¹ shown in Fig. 4, and the feeders 38 are adapted to move the cards A successively from the position shown at A¹ in Fig. 4 to the position shown at A² in Fig. 4, or upon the tympan 9.

To prevent the feeders 37 from moving more than one card at a time from the magazine 8, I provide the following: "The front wall 15 of the magazine has a vertically-adjustable panel 44 inserted into a guide opening therein and carried by a vertical screw 45 whose lower end is screwed into a projection 46 on the panel 44. The screw 45 is mounted to turn in a bracket 47 on the forward face of the front wall 15 of the magazine, vertical movement of the screw 45 within the bracket 47 being prevented by a head 48 and a collar 59 on the screw 45 above and below the bracket 47. It will thus be seen that by turning the screw 45 the panel 44 may be raised or lowered to permit cards of different thicknesses to be projected from within the magazine by the feeders 37."

The panel 44 is provided with a plate-like bar or projection 50 which extends therefrom a slight distance above the table 7 to a position near the tympan 9 and directly over the path traversed by the cards A from the magazine 8 to the tympan 9 to prevent upward buckling of the cards during the feeding thereof.

When the card feeders 37 and 38 are moved rearwardly from the position shown in Fig. 4 to the position shown in Fig. 3, the beveled upper surfaces of the feeders 37 raise the cards within the magazine until the forward edges of the feeders 37 escape the rearward edges of the cards within the magazine while the rearward wall 17 of the magazine prevents the cards A from moving with the feeders 37; and the beveled upper surfaces of the feeders 38 raise the card in the position shown at A¹ in Fig. 4 until the forward edges of the feeders 38 escape the rearward edge of the card shown at A¹ in Fig. 4.

When the feeders 37 and 38 are moved forwardly from the position shown in Fig. 3 to the position shown in Fig. 4, the forward edges of the feeders 37 engage the rearward edge of the lowermost card A in the magazine 8 and move it therefrom to the position shown at A¹ in Fig. 4; and the forward edges of the feeders 38 engage the rearward edge of the card previously moved by the feeders 37 to the position shown at A¹ and move it from the position shown at A¹ to the position shown at A² upon the tympan 9. After the movement of each card to the tympan 9 the next succeeding card in being moved from the position shown at the position A¹ to the position shown at A² engages the card upon the

tympan and moves it forwardly therefrom and discharges it into a chute 51 from which it may be put into any suitable receptacle or be discharged upon the table supporting the machine frame 6.

To prevent the card A in the position shown at A¹ in Fig. 4 from moving rearwardly with the feeders 38 as they pass beneath the card during the rearward movement of the feeders, I provide the following: Rising fixedly from the bar 50 is a screw or post 52 having a head 53 on the upper end thereof and fitted to slide vertically on the post 52 is a transversely extending block 54 which is pressed downwardly upon the bar 50 by a spring 55 encircling the post 52 between the head 53 thereon and the block 54. The ends of the block 54 have two horizontal bars 56 secured thereto and extending longitudinally over the path of movement of the two forward feeders 38. In the normal position of the block 54 the bottom surfaces of the bars 56 are slightly below the path of movement of the upper surfaces of the cards A, and the rearward ends of the bars 56 are provided with downwardly extending abutments 57 whose forward surfaces are adapted to engage the rearward edges of the cards in the position shown at A¹ and prevent rearward movement thereof. The bottom surfaces of the abutments 57 are beveled rearwardly and upwardly to permit the abutments to be raised out of the path of the cards as they are moved forwardly beneath the same. In the normal position of the bars 56 the bottom surfaces thereof are slightly below the path of the upper surfaces of the cards A, so that, when the cards are moved from the magazine 8 to the position A¹, the bars 56 and their abutments 57 will be raised by the cards against the action of the spring 55 and thereafter the spring 55 will press the bars 56 gently upon the cards so as to insure the engagement of the abutments 57 with the rearward edges of the cards and the consequent prevention of the rearward movement of the cards from the position shown at A¹ by the feeders 38 during the rearward movements of the feeders. As the feeders 38 are moved rearwardly beneath a card in the position shown at A¹ the beveled upper surfaces of the feeders 38 raise the card and therewith the bars 56 against the action of the spring 55 until the forward edges of the feeders 38 escape the rearward edge of the card, whereupon the spring 55 depresses the bars 56 and therewith the card beneath them, so that the rearward edge of the card will be in the path of movement of the forward edges of the feeders 38 to be moved thereby from the position shown at A¹ to the position shown at A². The tops of the feeders 38 are provided with clearance grooves 58

for the reception of the bars 56 and their abutments 57 during the reciprocations of the feeders 38.

The lower portion of the rear wall 17 of the magazine 8 is provided with two card supporting fingers 60 which extend forwardly therefrom into the central portions of the openings 49 in the table 7 and which are formed integral therewith. The upper surfaces of these fingers 60 are flush with the upper surface of the table 7, and the rearward feeders 37 are provided with clearance grooves 61 in the tops thereof for the reception of the fingers 60 when the feeders 37 pass the same. The purpose of the fingers 60 is to support the cards within the magazine 8 centrally of the openings 49 in the proper position relatively to the rearward feeders 37 to permit them to engage and move the lowermost card from the magazine as pressure is applied to the cards within the magazine by hand or other means during the operation of the machine.

I claim:

1. The combination of a supporting table provided with card guiding means, rearward and forward card feeders for feeding cards successively from a first position on the table to a second position thereon and from said second position to a third position, respectively, means for reciprocating the feeders, a spring pressed bar adapted to engage the top surfaces of the cards in the second position thereof, and an abutment extending downwardly from the bar and adapted to be engaged by the rearward edges of the cards when they are in the second position to prevent rearward movement thereof.

2. The combination of a supporting table provided with card guiding means, rearward and forward card feeders for feeding cards successively from a first position on the table to a second position thereon and from said second position to a third position, respectively, means for reciprocating the feeders, a spring pressed bar adapted to engage the top surfaces of the cards in the second position thereof, and an abutment extending downwardly from the bar and adapted to be engaged by the rearward edges of the cards when they are in the second position to prevent rearward movement thereof, said abutment having a beveled portion adapted to be engaged by the cards to move the abutment out of the path of the cards while they are passing it.

3. The combination of a supporting table provided with card guiding means, rearward and forward card feeders for feeding cards successively from a first position on the table to a second position thereon and from said second position to a third position, respectively, means for reciprocating the feeders, and an abutment movable into and from the path of the cards rearwardly

of said second position to prevent rearward movement of the cards therefrom, the forward card feeder having a beveled upper surface to raise the cards in the second position thereof during the rearward movement of the forward feeder.

4. The combination of a supporting table provided with card guiding means, rearward and forward card feeders for feeding cards successively from a first position on the table to a second position thereon and from said second position to a third position, respectively, means for reciprocating the feeders, and a spring pressed abutment movable into 10 and from the path of the cards rearwardly of said second position to prevent rearward movement of the cards therefrom, said abutment having a beveled portion adapted to be engaged by the cards to move the abutment out of the path of the cards while they are passing it, and the forward card feeder having a beveled upper surface to raise the cards in the second position thereof during the rearward movement of the forward feeder.

5. The combination of a supporting table provided with card guiding means, rearward and forward card feeders for feeding cards successively from a first position 30 on the table to a second position thereon and from said second position to a third position, respectively, means for reciprocating the feeders, a spring pressed bar adapted to engage the top surfaces of the cards in the second position thereof, and an abutment extending downwardly from the bar and

adapted to be engaged by the rearward edges of the cards when they are in the second position to prevent rearward movement thereof, said abutment having a beveled portion 40 adapted to be engaged by the cards to move the abutment out of the path of the cards while they are passing it, and the forward card feeder having a beveled upper surface to raise the cards in the second position 45 thereof during the rearward movement of the forward feeder.

6. The combination of a supporting table provided with card guiding means, rearward and forward card feeders for feeding cards successively from a first position on the table to a second position thereon and from said second position to a third position, respectively, means for reciprocating the feeders, a spring pressed bar above the path 50 of movement of the forward feeder and adapted to engage the top surfaces of the cards as they pass the bar, and an abutment 55 extending downwardly from the bar and adapted to be engaged by the rearward edges 60 of the cards when they are in the second position to prevent rearward movement thereof, said abutment having a beveled portion adapted to be engaged by the cards to move the abutment out of the path of the cards 65 while they are passing it, and said forward feeder having a clearance groove therein for the reception of said abutment.

In testimony whereof I affix my signature hereto.

MILLARD F. ATKINSON.
